(57) **CLAIM**

The ornamental design for a wheel, as shown and described.

DESCRIPTION

FIG. 1 is a front, right side, top perspective view of a wheel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged detailed view of the region 8 noted upon FIG. 1.

The broken lines depict portions of the wheel that form no part of the claimed design. The dot-dash-dot broken lines in FIGS. 1 and 8 depict the boundaries of the detailed enlargements that form no part of the claimed design.
